CLAIM

The ornamental design for a cosmetic skin care device, as shown and described.

DESCRIPTION

1. Cosmetic skin care device

Figure 1.1 is a perspective view of a cosmetic skin care device showing our new design;

Figure 1.2 is a front view thereof;

Figure 1.3 is a back view thereof;

Figure 1.4 is a left view thereof;

Figure 1.5 is a right view thereof;

Figure 1.6 is a top view thereof; and

Figure 1.7 is a bottom view thereof.

The broken lines shown in the figures are for the purpose of illustrating portions of the cosmetic skin care device, which form no part of the claimed design.

1 Claim, 7 Drawing Sheets
